(57) **CLAIM**

The ornamental design for a radiator grill for an automobile, as shown and described.

DESCRIPTION

FIG. 1 is a front elevational view of a radiator grill for an automobile in accordance with our new design;

FIG. 2 is a top plan view of the radiator grill in accordance with our new design of FIG. 1;

FIG. 3 is a bottom plan view of the radiator grill in accordance with our new design of FIGS. 1 and 2;

FIG. 4 is a left side elevational view of the radiator grill in accordance with our new design of FIGS. 1 to 3;

FIG. 5 is a right side elevational view of the radiator grill in accordance with our new design of FIGS. 1 to 4;

FIG. 6 is a front-right side perspective view of the radiator grill in accordance with our new design of FIGS. 1 to 5; and, FIG. 7 is a cross-sectional view of the radiator grill in accordance with our new design of FIGS. 1 to 6 as taken along a section line 7-7 in FIG. 1.

The broken line showing of the radiator grill is for purpose of illustrating environmental structure and forms no part of the claimed design. The rear view of the radiator grill forms no part of the claimed design.

The cross sectional view of FIG. 7 is provided to clarify the exact contour or configuration of the exterior surface of the radiator grill, and no attempt is made to illustrate features of internal construction.
